UNITED STATES PATENT OFFICE.

CHARLES A. PIKE, OF PAW PAW, MICHIGAN.

WEATHER-STRIP.

No. 882,343.

Specification of Letters Patent. Patented March 17, 1908.

Application filed August 26, 1907. Serial No. 390,211.

To all whom it may concern:

Be it known that I, CHARLES A. PIKE, a citizen of the United States, residing at the village of Paw Paw, county of Van Buren, 5 State of Michigan, have invented certain new and useful Improvements in Weather-Strips, of which the following is a specification.

This invention relates to improvements in weather strips for doors.

10 The main objects of this invention are: first, to provide an improved weather strip for doors by which the wear on the floor or door sill and on the weather strip is reduced to a minimum. Second, to provide an improved 15 proved weather strip for doors adapted to form a very tight joint when the door is closed, and one which does not materially add to the power required to open or close the door. Third, to provide an improved 20 weather strip for doors embodying the above features, which is automatically controlled by the opening and closing of the door, it being adapted to automatically open on the opening of the door and to automatically 25 close on the closing of the door. Fourth, to provide an improved weather strip for doors embodying the above advantages which is a simple and economical structure and may be readily applied without in any way mutilating 30 the door to which it is applied.

Further objects, and objects relating to structural details, will definitely appear from the detailed description to follow.

I accomplish the objects of my invention 35 by the devices and means described in the following specification.

The invention is clearly defined and pointed out in the claims.

A structure embodying the features of my 40 invention is clearly illustrated in the accompanying drawing, forming a part of this specification, in which,

Figure 1 is a detail elevation of a structure embodying the features of my invention, the 45 open position of the parts being indicated by dotted lines. It will be understood, however, that they do not assume this position while the door is closed. Fig. 2 is an enlarged detail section taken on a line corresponding to line 2—2 of Fig. 1. Fig. 3 is a detail section through the levers 8, taken on a line corresponding to line 3—3 of Fig. 1, showing the connection for the levers. Fig. 4 is a detail vertical section, taken on a line

corresponding to line 4—4 of Fig. 1, showing 55 details of the weather strip or plate-lifting lever.

In the drawing, the sectional views are taken looking in the direction of the little arrows at the ends of the section lines, and 60 similar numerals of reference refer to similar parts throughout the several views.

Referring to the drawing, 1 represents the wall of a building; 2 the door frame or casing; and 3 the floor or door sill. The door 4 65 is hung on suitable hinges, but as these form no part of this invention they are not here illustrated.

The weather strip or plate 5 is arranged across the bottom of the door, and secured 70 thereto by the screws 6 which are arranged in the vertical slots 7 in the plate. These screws also serve as supports for the levers 8, which are pivotally mounted thereon. The levers 8 are pivotally connected at their 75 outer ends as by the screws 9 to the plate. The inner ends of the levers are connected by the rivet 10 carried by one of the levers, which is adapted to engage a suitable slot, as 11, in the other. By this connection the 80 plate is guided so that it is impossible for it to wedge or bind in its movement in opening or closing.

The weather strip or plate is preferably provided with a facing 12 of felt, rubber or 85 other suitable material, for its lower edge.

The inner ends of the levers 8 are held normally upward by means of the spring 13, the free end of which is connected thereto by suitable link as 14, the other end of the 90 spring being mounted upon the plate by means of a suitable stud 15.

It is obvious that through the connection of the levers to the door, when their inner ends are held upward, the weather strip or 95 plate is thrown down to the position indicated by full lines in the drawing.

When the door is open, the plate is elevated by means of the lever 16 which is actuated by a spring 17. The spring 17 is connected to the lower end of the lever and to the stud or post 18 projecting through a slot 19 provided therefor in the plate, the stud being carried by the door. The lever 16 is provided with a curved arm 20 which is 100 adapted to engage the pin 21 on the plate, so that the spring serves to hold the plate normally upward. This spring is of sufficient 105

strength or tension to overcome the tension of the spring 13, so that, unless the lever 16 is held out of its engaging position, the plate is held normally upward.

5 The lever 16 is arranged vertically and is mounted on a suitable pivot as 22, arranged through a vertical slot 23 in the plate, as clearly appears in Fig. 4. When the door is closed, the lever is engaged by the trip pin 24 which forces its upper end inwardly, thereby releasing the plate 5, allowing the spring 13 to close the same. As soon, however, as the door is open, the lever is released, so that the spring 17, acting therein, lifts the plate 15 against the tension of the lever 13, holding it open. By this simple means, I secure a weather strip for doors, which, while it is very tight when closed, is automatically opened upon the opening of the door so that 20 the wear on the weather strip and upon the door sill or floor is minimized, it being in fact practically nothing. The structure is very simple and at the same time strong and durable.

25 I have illustrated my improved weather strip in detail in the form preferred by me on account of its structural simplicity and economy. I am, however, aware that it is capable of considerable variation in structural details without departing from my invention.

Having thus described my invention, what I claim as new and desire to secure by Letters Patent is:

35 1. The combination with a door, of a plate having vertical slots therein; screws arranged through said slots for securing said plate to said door; a pair of levers mounted on said screws, pivotally connected to each other at their inner ends, and to said plate at their outer ends; a closing spring carried by said plate for applying tension to said levers, said spring being connected to the inner ends of said levers to lift the same, whereby said plate is forced downwardly; a vertically-arranged plate lifting lever provided with a laterally projecting curved arm; a pin on said plate arranged to be engaged by said arm; a pivot for said plate lifting lever; a post projecting from said door, said plate having vertical slots therein to receive said post and said pivot for said plate lifting lever; a spring connected to said post and to said plate lifting lever, said spring being of sufficient strength to raise said plate against the tension of said closing spring; and a trip pin adapted to actuate said plate lifting lever to release said plate when the door is in its closed position.

60 2. The combination with a door, of a plate having vertical slots therein; screws arranged through said slots for securing said plate to said door; a pair of levers mounted on said screws, pivotally connected to each other at their inner ends, and to said plate at their

outer ends; a closing spring carried by said plate for applying tension to said levers, said spring being connected to the inner ends of said levers to lift the same, whereby said plate is forced downwardly; a plate lifting lever; a pin on said plate arranged to be engaged by said lever; a pivot for said plate lifting lever; a post projecting from said door, said plate having vertical slots therein to receive said post and said pivot for said plate lifting lever; a spring connected to said post and to said plate lifting lever, said spring being of sufficient strength to raise said plate against the tension of said closing spring, and a trip pin adapted to 70 actuate said plate lifting lever to release said plate when the door is in its closed position.

3. The combination with a door, of a plate having vertical slots therein; screws arranged through said slots for securing said plate to said door; a pair of levers mounted on said screws, pivotally connected to each other at their inner ends, and to said plate at their outer ends; a vertically arranged plate lifting lever provided with a laterally projecting curved arm; a pin on said plate arranged to be engaged by said arm; a pivot for said plate lifting lever; a post projecting from said door, said plate having vertical slots therein to receive said post and said pivot for said plate lifting lever; a spring connected to said post and to said plate lifting lever; and a trip pin adapted to 80 actuate said plate lifting lever to release said plate when the door is in its closed position.

4. The combination with a door, of a plate having vertical slots therein; screws arranged through said slots for securing said plate to said door; a pair of levers mounted on said screws, pivotally connected to each other at their inner ends, and to said plate at their outer ends; a plate lifting lever; a pin on said plate arranged to be engaged by said plate lifting lever; a pivot for said plate lifting lever; a post projecting from said door, said plate having vertical slots therein to receive said post and said pivot for said plate lifting lever; a spring connected to said post and to said plate lifting lever; and a trip pin adapted to 90 actuate said plate lifting lever to release said plate when the door is in its closed position.

5. The combination with a door, of a plate adjustably mounted thereon; a pair of pivotally mounted levers connected to each other, and to said plate; a closing spring carried by said plate for applying tension to said levers; a vertically-arranged pivoted plate-lifting lever provided with a laterally projecting curved arm; a pin on said plate arranged to be engaged by said arm; a spring connected to said door and to said plate lifting lever, said spring being of sufficient strength to raise said plate against the tension of said 100

115

closing spring; and a trip pin adapted to actuate said plate lifting lever to release said plate when the door is in its closed position.

6. The combination with a door of a plate 5 adjustably mounted thereon; a pair of pivotally mounted levers connected to each other, and to said plate; a closing spring carried by said plate for applying tension to said levers; a plate-lifting lever; a spring connected to 10 said door and to said plate lifting lever, said spring being of sufficient strength to raise said plate against the tension of said closing spring; and a trip pin adapted to actuate said plate lifting lever to release said plate 15 when the door is in its closed position.

7. The combination with a door, of a plate adjustably mounted thereon; a pair of pivotally mounted levers connected to each other and to said plate; a closing spring carried by said plate for applying tension to said levers; a vertically-arranged pivoted plate-lifting lever provided with a laterally projecting curved arm; a pin on said plate arranged to be engaged by said arm; and a 25 spring connected to said door and to said plate lifting lever, said spring being of sufficient strength to raise said plate against the tension of said closing spring; and means for actuating said plate lifting lever to release said plate when the door is in its closed position.

8. The combination with a door, of a plate adjustably mounted thereon; a pair of pivotally mounted levers connected to each other

and to said plate; a closing spring carried by 35 said plate for applying tension to said levers; a plate-lifting lever; a spring connected to said door and to said plate lifting lever, said spring being of sufficient strength to raise said plate against the tension of said closing 40 spring; and means for actuating said plate lifting lever to release said plate when the door is in its closed position.

9. The combination with a door, of a plate adjustably mounted thereon; a plate-closing 45 spring; a plate-lifting lever; a spring connected to said door and to said plate-lifting lever, said spring being of sufficient strength to raise said plate against the tension of said closing spring; and means for actuating said 50 plate-lifting lever to release said plate when the door is in its closed position.

10. The combination with a door, of a plate adjustably mounted thereon; a plate-closing spring; a plate-lifting spring, said 55 plate-lifting spring being of sufficient strength to raise said plate against the tension of said closing spring; and means for releasing said plate off the action of said plate-lifting spring when said door is in its closed position. 60

In witness whereof, I have hereunto set my hand and seal in the presence of two witnesses.
